UNITED STATES PATENT OFFICE.

THOMAS C. WHITEHEAD AND FRED J. HEIDEMAN, OF DETROIT, MICHIGAN; SAID HEIDEMAN ASSIGNOR TO SAID WHITEHEAD.

CONDENSER.

Application filed February 1, 1926. Serial No. 85,290.

This invention relates generally to refrigerating apparatus and consists of certain novel features of construction, combinations and arrangements of parts as will be herein-
5 after more fully described and particularly pointed out in the appended claims.

In the accompanying drawings:

Figure 1 is a side elevation of an apparatus embodying our invention.

10 Figure 2 is a top plan view of our construction.

Figure 3 is a fragmentary section thereof.

Figure 4 is a detail view of a slightly modified form of condenser construction.

15 Figure 5 is a fragmentary sectional view taken substantially on the line 5—5 of Figure 2; and Figure 6 is a fragmentary end view of the condenser.

Referring now to the drawings, 1 designates a stand having a substantially flat top 2 upon which we preferably mount a pump 3 for compressing a refrigerating medium, a motor 4 for driving the pump, and a condenser 5 through which the compressed me-
20 dium passes to be cooled and condensed before entering the usual brine tank (not shown). In the present instance, the pump 3 and motor 4 may be of any suitable construction and are operatively connected by

25 a short shaft 6 that carries a fan 7, while the condenser 5 comprises a series of oblong coils 8 that are preferably arranged in superposed relation upon a relatively large tube 9 anchored in a suitable trough-shaped recess 10 in the top 2 of the stand. As shown, the uppermost coil 8 has a lateral extension 11 that is connected to the pump 3, while the lowermost coil has a lateral extension 12 that is preferably connected to a suitable nipple 13 projecting outwardly from the inner side of the tube 9. To provide an efficient construction, the tubing forming the coils 8 and extension 11 and 12 has a relatively small diameter preferably $\frac{3}{8}$ " or $\frac{1}{2}$ " and is pro-
30 vided with a correspondingly restricted pas-
sage for the refrigerating medium. Thus,
the flow of the compressed gases through the coils is retarded by the restricted passage in the tubing, consequently the volume of the
35 compressed gases passing through the tubing is reduced. As a result the tubing will radiate more rapidly the heat of the gases and will cause such gases to be condensed quickly and thoroughly.

40 45 50 55 The tube 9 constituting the base for the

coils 8 has a relatively large diameter and serves as a reservoir for the condensed refrigerating medium. As shown, this tube is provided with a sight opening 14 for disclosing the level of the refrigerating medium therein and has a suitable outlet opening 15 through which the refrigerating medium may flow to a suitable tube (not shown) leading to the brine tank. Preferably these openings 14 and 15 respectively are located in removable heads 16 and 17 at the opposite ends of the tube. As shown, the sight opening 14 in the head 16 is closed by a suitable piece of glass 18 which is held in position by a gland 19, while the outlet opening 15 in the head 17 is preferably tapered and is adapted to receive the stem or shank of a suitable valve (not shown) to which the tube leading to the brine tank is preferably connected. Thus, with this construction, the level of the liquid in the tube 9 may be readily ascertained through the glass 18 at any time. This is especially advantageous at the time the apparatus is installed when it is desirable to know the quantity of the refrigerating me-
60 dium in the system.

To provide a strong and durable construction, the coils 8 are preferably held upon the tube 9 by means of a light sheet metal frame 20 while the tube 9 is preferably held in the trough-shaped recess 10 by means of the arcuate-shaped straps 21. As shown, the frame 20 is substantially U-shaped and is arranged in inverted position within the coils 8. To insure rigidity the sides 22 of the frame are preferably corrugated to conform to the curvature of suitable fins 23 surrounding the tubing and are provided at their lower ends with inturned feet 24 that are rigidly secured, preferably by welding to the top of the tube 9. The straps 21 preferably extend over the feet 24 and are terminally secured, preferably by the bolts 25, to the top 2 of the stand. Rigidly secured to the top 26 of the frame is a name plate 27 which constitutes a cover for the coils 8 and an anchorage plate for an inverted trough-shaped hood 28. As shown, the top wall 29 of the hood is hingedly connected to the name plate 27 while the depending side walls 30 normally project forwardly to approximately the median line of the coils 8 and extend downwardly around the tube 9 to the top 2 of the stand. Thus this hood normally cooperates with the stand top to form an air duct between the condenser 70 75 80 85 90 95 100 105 110

5 and fan 7. When the apparatus is in operation air will be drawn by the fan 7 through the condenser 5 and over the pump 3 and will be discharged toward the motor 4, hence the 5 cooling and condensing of the compressed refrigerating medium passing through the radiator will be expedited. Moreover the constant flow of air will tend to cool the pump 3 and motor 4.

10 In Figure 3 we have shown a slightly modified condenser construction in which the uppermost coils 11', preferably the first three, are formed of $\frac{5}{16}$ " or $\frac{3}{8}$ " tubing, while the lower coils are preferably formed of $\frac{3}{16}$ " 15 or $\frac{1}{8}$ " tubing. Thus this $\frac{5}{16}$ " or $\frac{3}{8}$ " tubing will restrict the flow of gases through the lower coils and will cause the flow of gases in the $\frac{5}{16}$ " and $\frac{3}{8}$ " tubing of the upper coils to be retarded. As a result the $\frac{5}{16}$ " or $\frac{3}{8}$ " 20 tubing will radiate more rapidly the heat of the reduced volume of gases passing therethrough, while the $\frac{5}{16}$ " or $\frac{3}{8}$ " tubing will have a better opportunity to radiate the heat of the larger volume of gases.

25 While it is believed that from the foregoing description, the nature and advantage of our invention will be readily apparent, we desire to have it understood that we do not limit ourselves to what is herein shown 30 and described and that such changes may be resorted to when desired as fall within the scope of what is claimed.

What we claim as our invention is:

1. In a refrigerating apparatus, the combination with a stand, of a condenser having a tubular base secured thereto, a plurality of coils of tubing arranged in superposed relation, and means for holding the coils in position including a frame secured to the base.
- 40 2. In a refrigerating apparatus, the combination with a stand, of a condenser having a tubular base secured thereto, a plurality of coils of tubing arranged in superposed relation, and means for holding the coils in position including an inverted substantially U-shaped frame having feet secured to the base.
- 45 3. In a refrigerating apparatus, the combi-

nation with a stand, of a condenser having a tubular base secured thereto, a plurality of coils of tubing arranged in superposed relation, fins on said tubing, and means for holding the coils in position including a frame within the coils having corrugated portions engageable with said fins.

4. In a refrigerating apparatus, the combination with a stand, of a condenser having a tubular base secured thereto, a plurality of coils of tubing arranged in superposed relation, and means for holding the coils in position including a substantially U-shaped frame arranged in inverted position on the base, the top of the frame being above the uppermost coil and the sides of the frame being within the coils and secured at their lower ends to the base.

5. In a refrigerating apparatus, the combination with a stand, of a condenser having a tubular base and a plurality of coils of tubing arranged in superposed relation, means for holding the coils in position including a frame secured to the base, and means for holding the base in position including a strap anchored on the stand embracing said base.

6. In a refrigerating apparatus, the combination with a stand, of a condenser having a hollow base positioned upon the stand, a plurality of coils of tubing arranged in superposed relation, a frame for holding the coils in position, and common means for securing said frame and hollow base upon the stand.

7. In a refrigerating apparatus, the combination with a stand, of a condenser having a tubular base positioned upon the stand, a plurality of coils of tubing arranged in superposed relation, a frame for holding said coils in position, and a strap embracing portions of said frame and tubular base, said strap having laterally projecting portions rigidly secured to the stand.

In testimony whereof we affix our signatures.

THOMAS C. WHITEHEAD.
FRED J. HEIDEMAN.
